TRAVELING CRANE

Benjamin F. Fitch, Greenwich, Conn., assignor
to Motor Terminals Company, New York, N. Y.,
a corporation of Delaware

Application December 10, 1934, Serial No. 756,858

12 Claims. (Cl. 212—126)

This invention relates to a traveling crane adapted to lift and transport demountable automobile bodies or containers with their loads, to effect the transference between different vehicles or between a vehicle and a station platform or support. The traveling frame of the crane may be mounted to move transversely on a bridge carried by elevated supports or may be on top of a gantry, as desired. In either case I have provided four cables depending from winding drums and adapted to be secured at four corners of a rectangle directly to the container or to a cradle which may be attached to such container, and I provide means by which two of said cables may be shifted laterally as a unit with reference to the other two, so that the area served by the cables may be effectively registered with a truck which need not stand in exact parallelism with the crane.

The present application is a continuation in part of my application Ser. No. 723,112, filed April 30th, 1934. Among the objects stated in that parent case is the provision of transmission mechanism between the raising motor and the cable drums in the form of standard driving axle construction of automobile trucks. Such mechanism is underslung from the crane frame so that it may be lowered intact for repairs whenever necessary. Such features being also shown in this case, reference is made to the parent application for claims thereon.

The invention of the present application is concerned particularly with provisions for power operated weaving, that is, shifting the cables which support one end of the body toward one side or the other of the frame to enable the proper engagement with the body not accurately aligned with the frame, or to deposit the lowered body on a truck frame not so aligned. In prior applications of mine I have effected this weaving by shifting sheaves over which cables depend. By the present invention I am enabled to effect the result more directly by shifting the cable drums themselves, and this enables the cables at both the fixed and shifting ends of the frame to depend directly from the cable drums to a suitable suspended cradle which may engage a demountable body.

The raising and weaving mechanism I have provided, and which is included in this invention, is powerful and at the same time compact, and requires comparatively small space, so that it may be mounted almost entirely within the confines of the crane frame itself. The raising, weaving and trolleying mechanisms are all of a self-

locking nature, thus avoiding necessity of brakes of any sort. The crane frame carrying such mechanisms may be mounted on any suitable support, either stationary or part of the traveling crane bridge, or at the top of a gantry, as desired.

The details of my invention will become apparent from the description about to be given of a preferred embodiment thereof, illustrated in the drawings hereof.

In the drawings, Fig. 1 is a side elevation of a crane embodying my invention, this view showing the lifting members attached to a demountable body which is suspended thereby above the trailer of a highway truck; Fig. 2 is a plan of the construction of the part shown in Fig. 1; Fig. 3 is a plan on a larger scale, of the crane proper; Figs. 4 and 5 are vertical longitudinal sections of the crane in the planes indicated by the lines 4—4 and 5—5 respectively on Fig. 3; Fig. 6 is a detail in vertical section of one of the four cable drums, as indicated, for instance, by the line 6—6 on Fig. 3; Fig. 7 is a fragmentary elevation of a portion of the weaving mechanism, the location being indicated by the line 7—7 on Fig. 3; Fig. 8 is a vertical section through the worm reduction gearing for operating one of the cable drum units, as indicated by the correspondingly numbered line in Fig. 3; Fig. 9 is a vertical section through the worm reduction gear of the weaving mechanism as indicated by the line 9—9 on Fig. 3; Fig. 10 is a vertical section through the worm reduction gear of the mechanism for propelling the crane frame, as indicated by the line 10—10 on Figs. 3 and 5.

As shown in Figs. 1, 2 and 3, the mechanism of my crane is carried by a traveling, rectangular, horizontal frame 10, which carries supporting wheels 20 riding on suitable supported rails 5. The rectangular frame work of the crane, as shown in Fig. 3, comprises two side members 11, 12, and two end members 13, 14, and four intermediate members 15, 16, 17 and 18, parallel with the end members. Between each end member and the adjacent cross member are wheels 20, supported by bearings on such members and adapted to ride on the guide rails 5 of the bridge. There are four of these wheels, one substantially in each corner of the rectangle forming the frame work.

Two of the wheels 20, one on each track 5, furnish the driving means for the frame across the bridge. A motor 21, supported by frame bars 22, drives a worm 23 meshing with a worm wheel 24 (Fig. 10) in a casing 29 on a long shaft 25, ex-

tending across the bridge. At each end of the shaft 25, which is journaled in the frame 10, are pinions 26. These pinions engage internal gears 27 in the corresponding wheels 20 to drive the wheels as the motor 21 is electrically excited. The longitudinal transmission shaft 25, which is preferably made of separate aligned connected sections extends through the various frame members, and if desired may have bearings mounted thereon and suitable couplings 28 allowing sufficient flexibility to prevent binding.

Two of the raising cables 31, 32, are mounted on winding drums 35, which are rotated, but do not shift axially, while the other two cables 33, 34 are mounted on similar drums 36, which, to effect the weaving of this invention, as herein-after described, may be shifted axially. I will describe first the means for supporting and operating the drums 35, shown near the bottom of Fig. 3, and near the right-hand end of Fig. 5.

The cable drums 35 and the housings 50 which carry them and contain their driving axles, are mounted between the frame beams 15 and 16, and thus stand close to the supporting wheels 20. This construction reduces the bending moment of the crane frame and allows the frame to be made of lighter construction than otherwise. The peculiar construction of the transmission mechanism to the cable drum, which, as heretofore explained, is of standard automobile construction and suspended by the frame members, and which is claimed in my parent application, is here shown in Figs. 3, 4, 6 and 8. In those figures 50 indicates a hollow housing which has an enlarged central portion of approximately spherical form 51, and lateral extending tubular portions 52. These tubular portions are approximately square, as shown in Fig. 4, and mounted between a pair of clamping plates 55 and 56 and held by vertical bolts 57 passing through these clamping plates and through another plate 58, which rests on top of short frame beams 59, extending between the frame beams 15 and 16 and rigidly connected to them. Thus, the housing is effectively suspended from the crane frame and lies partially in the space between transverse members 15 and 16.

Within the center portion of the housing 51 is a suitable worm wheel 60 (Fig. 8) rigidly connected with the two aligned driving axles 61 (Fig. 6), which are connected at their ends, as herein-after described, to the cable drums 35. The driving mechanism, hereinabove described, operates a worm 64 within the housing below the worm wheel, with which it meshes. On the outer end of each axle 61 is a head 65, which is bolted to a sleeve 66, surrounding the housing 52 and journaled thereon by means of interposed roller bearings 67 and 68, the bearing space being closed by a grease washer 69 after the manner of the standard mounting and connection of the hub of an automobile driving wheel.

The cable drum 35 is a hollow member having on its exterior an annular region bounded by circular ribs 71 and 72 for the reception of various turns of the cable. Beyond this cable region the drum extends as a sleeve 75 terminating in an outward flange 76. This flange is bolted to an annular flange 77, formed on the exterior of the hub sleeve 66. At its other end the cable drum has an end wall 78, with a central hub 79, in which is rigidly mounted a stub shaft 80. This shaft extends into a roller bearing 81, mounted in a cage 82 which, by means of a flange 83, is bolted to the web of a short channel beam 85,

which has its ends rigidly secured to the cross beams 15 and 16 of the crane frame.

The arrangement for supporting and driving the cable drums at the weaving end of the crane which is shown near the top of Fig. 3 and near the left-hand of Fig. 4, is identical with that described, except that the housing and drums, instead of being mounted on the rigid frame, are mounted on a shiftable carriage 90, composed of a pair of main beams 91, end beams 92, and intermediate beams 93. The intermediate beams 93 correspond to the beams 59, which support the housing 50 at the other end, and carry corresponding plates 95 and bolts 96 by which the housing 100 is suspended. The winding drums 36 at this end are journaled on the housing and connected to the drive shafts, and the end supporting studs are journaled in roller bearings in the cage 98, secured to the end beams 92 in the manner heretofore described.

The carriage 90, in which the drums 36 and their driving mechanism within the housing 100 are mounted, is provided with four laterally projecting studs on which are supporting wheels 110, which track on rails 111 and 112, rigidly supported on the frame beams 17 and 18. To shift the cradle one way or the other, as desired, I provide a motor 120, the armature shaft 121 of which is connected by a suitable coupling with a worm 122, meshing with a worm wheel 123 (Fig. 30 9), journaled in a housing 124 secured to the frame beam 17. The worm wheel is on a shaft 125, which carries a crank 126 (Fig. 7) having a roller 127 on its crank pin, which lies between a pair of vertical gibs 128 secured to the side 35 member 91 of the carriage.

It results from the construction described that when the motor 120 is energized the moving crank pin travels in the space between the gibs 128 after the manner of a scotch yoke and thus shifts 40 the carriage 90 in one direction or the other. This shifting, if allowed to continue for a complete rotation of the shaft 125, would move the carriage to the limit in one direction and then reverse it and move it to the limit in the other 45 direction, and accordingly, it is not necessary to have a reversing motor, as I can obtain a shift in either direction by allowing the carriage to move first in the other direction and then return. However, as the movement of the carriage is 50 comparatively slow, it is entirely feasible to provide a reversing motor and actuate it in one direction or the other according to the direction of shift desired for the carriage.

The worm 103, which drives the worm wheel 55 102 (Fig. 4) at the weaving end is in the same horizontal plane as the worm 64 at the fixed end. Both these worms are driven simultaneously by a common motor. However, the connection to the carriage worm employs an extensible universal 60 shaft to enable the drive to be effected for any position of the carriage. The mechanism for driving these two worms will now be described.

Extending longitudinally of the crane frame in a central region are parallel beams 130, spaced 65 apart. Beneath the region between these beams is suitably suspended a housing 132, having a central chamber and extending sleeves 133 similar to that heretofore described but preferably of smaller construction. Each of the sleeves 133 70 is embraced by plates through which pass bolts 134, securing the housing to brackets 135, depending from the frame beams 130. Within the housing 132 is a driving worm 140 connected by a suitable coupling with the armature shaft 141 75

of a motor 144, supported by frame beams 145 leading from the adjacent beam 130 to the side beam 12.

Within the housing 132 is a worm wheel 150 (Fig. 4) meshing with the worm 140 and rigid with two aligned axles, one of which extends out of the housing and is suitably coupled as at 151 to the worm 64. The axle at the other end extends within a suitably supported bearing member 152 and terminates in one member of a gimbal joint 153 connecting it to a universal shaft 155. This shaft is tubular and slidably receives a splined extension 156 of a shaft 157, which is connected by a gimbal joint 158 with the worm 103. The telescoping universal shaft accordingly maintains continuous driving connection between the axle in the housing 132 and the worm 103 of the weaving unit. Accordingly, when the motor 144 is energized the rotation is simultaneously transmitted to all four of the cable drums, operating them to the same extent to wind the cables in or out, and thus raise or lower the body while maintaining it level. This action is entirely independent of the weaving, which may take place during the raising or lowering of the load.

The four depending cables 31, 32, 33, 34, may, if desired, be directly connected to the load, as, for instance, to the lift hooks *a* at the eaves of the demountable body A in Fig. 1, or I may employ a rectangular floating cradle 160 (Figs. 1 and 5) having depending loops or shackles 161, which may engage such lift hooks, the cables being connected to this cradle. The cradle shown has sheaves 163, which may be journaled about the same bolts 164 which carry the shackles, the cables extending in bights about these sheaves. As shown, the upper ends of the cables 31 and 32 are attached to hooks 165, secured to the cross frame beam 15, while the corresponding reaches 40 of the cables 33 and 34 are attached to hooks 166 secured to the carriage beam 91.

It will be understood from the description given that the body, notwithstanding its heavy load, may be readily raised by a comparatively light motor, and the weaving of such body is likewise effected by a light motor through the worm reduction gearing. Similarly a light motor may effect the propulsion of the crane. It will be noticed that all of the worm gears are encased in suitable housings to enable them to be packed in grease; rolling bearings of standard construction are employed throughout; suitable means are provided for making adjustments from time to time in the mesh of the gears.

I claim:

1. The combination, in a hoist, of a rigid frame adapted to span and ride on spaced tracks, a cable drum mounted thereon, a movable carriage on the frame, a cable drum mounted on the carriage, common means for simultaneously supplying power to the two drums, and power means for shifting the carriage.

2. The combination of a substantially rigid horizontal frame, a pair of cable drums mounted therein, driving mechanism for said drums, a movable carriage on the frame within the horizontal limits of the frame, a pair of cable drums mounted in the carriage, mechanism for moving the carriage axially of its drums, and four cables anchored to the four drums and depending therefrom.

3. In a crane, the combination of a substantially rigid frame, a drum and driving gearing therefor suspended from the frame, a carriage 75 on the frame within the limits of its rigid por-

tions, another drum and driving gearing mounted on the carriage, means for operating the said driving gearing, and power mechanism for shifting the carriage.

4. In a traveling crane, the combination of a frame, an automobile-driving-axle type housing fixedly suspended from the frame, a carriage movable on the frame, another automobile-driving-axle type housing fixedly suspended from the carriage, reduction gearing and lateral shafts in the respective housings, raising drums mounted on both ends of each of the housings connected to the respective shafts, a raising motor and transmission mechanism between said motor and the two reduction gearings.

5. The combination of a frame having mutually rigid spaced sides and ends, a self-contained unit mounted on the frame, said unit comprising, a hollow beam, a pair of cable drums supported on the beam and mechanism in the hollow beam for driving said drums, a carriage on the frame and shiftable with respect to said sides and ends, another self-contained unit comprising, a hollow beam mounted on the carriage, a pair of cable drums mounted on the beam, and mechanism in the beam for driving the drums, four cables depending from the four drums, and means for shifting the carriage.

6. The combination of a frame the parts of which are mutually rigid, a pair of cable drums in fixed position thereon, mechanism for driving the same mounted on the frame, a shiftable carriage mounted on the frame and supported thereby, a pair of cable drums and mechanism for driving the same mounted on the carriage, power mechanism mounted on the frame and coupled with both of said driving mechanisms, cables wound about said drums, and means for shifting the carriage.

7. The combination of an overhead traveling frame having horizontally spaced mutually rigid parallel ends, a carriage removably mounted thereon between said ends, a rigid housing suspended on the underside of the carriage, reduction gearing and a driving shaft within the housing, a raising drum connected with the shaft and supported in part by the housing, and coacting mechanisms mounted on the crane frame and carriage for moving the carriage.

8. In a traveling crane, the combination of a frame, a carriage movably mounted thereon, a raising drum mounted in the carriage, said carriage having an upright guideway, on one side thereof, a crank on the crane frame beside the carriage and having a pin occupying the guideway, and a motor on the crane frame for actuating the crank to reciprocate the carriage.

9. The combination of a crane frame having spaced mutually rigid ends, a movable carriage mounted on the frame and wholly supported thereby between said ends, a pair of winding drums on the carriage, driving mechanism in the carriage connected with the winding drums, a motor on the frame, oscillatory mechanism driven by the motor and connected with the carriage to reciprocate the carriage, and a lifting motor on the crane frame connected with the driving mechanism on the carriage.

10. An overhead hoist comprising a generally rectangular frame having rigidly connected opposite side and end members, a pair of self-contained hoisting units each including a pair of cable-winding members, driving shafting therefor, a common housing containing and supporting the shafting, and driving gearing in the hous- 75

- ing for operating said shafting; movable means on the frame for supporting the housing of one of said units for movement parallel to the axes of the winding members thereof, a power unit on 5
the frame located between said hoisting units, and driving means connecting the same with the respective driving gearings of the units, said driving means including flexible extensible means to maintain the driving connection to the movable 10 hoisting unit.
11. An overhead hoist comprising a frame having spaced side frame members and means rigidly connecting said members, two hoisting units each including a pair of cable actuating 15 members and driving means interconnecting the actuating members of each pair, a support between the frame members for one of said units, said support being fixed relative to the frame members, a carriage between the frame members 20 supporting the other unit, a trackway on the said

connecting means of the frame for supporting the carriage, power means for operating the driving means of said units, and separate power means for shifting the carriage.

12. An overhead hoist comprising a substantially rigid horizontal frame, two parallel hoisting units located within the horizontal limits of the frame, a rigid support on the frame for one unit, a carriage movably mounted on the frame for supporting the other unit, a driving motor 10 and a common driving means therefrom to both said units for operating them simultaneously, said means including a flexible driving connection to the carriage supported unit, a separate motor and reduction gearing therefor supported on the 15 frame and disposed adjacent the carriage, and a reciprocating device connecting the gearing with the carriage for moving one unit with reference to the other.

BENJAMIN F. FITCH. 20
